AIR CONDITIONING

Norman J. Urquhart, East Lansing, Mich., assignor to Humidex Corporation, a corporation of Michigan

Application January 12, 1939, Serial No. 250,548

4 Claims. (Cl. 257—121)

This invention relates to air cooling apparatus and has for its primary object to cool air by transferring heat therefrom to the low temperature earth at or beneath the water table.

5 The apparatus is adaptable for cooling almost any kind of a building and for other purposes.

Another object is to provide an air cooling system embodying conduits located beneath the surface of the earth, for receiving warm air from a building, for dissipating heat from the air into the earth, and for returning the air to the building at a substantially reduced temperature. More particularly it is an object of this invention 10 to teach how to obtain heat conductive contact between conduits and earth in such manner that large and continuous flow of fluid through conduits may be cooled.

Under seasonal or climatic conditions resulting in air temperatures approaching 90° F. a wide 20 temperature variance exists between the air and the earth below the water table which is at approximately 50° F. The earth above the water table, being unsaturated, is at a higher temperature than that below the water table, and ordinarily is a poor heat conductor. Therefore, an air circulating system located in the earth above the water table is not capable of dissipating heat as rapidly as one located beneath the water table. However, due to the depth of an excavation necessary to place an air circulating system beneath 25 the water table level, such procedure is, in some cases, impractical. This invention has for another object to teach the manner in which an air circulating system may be located in the earth above the water table and the heat transferred from the air and conducted to and dissipated in the earth below the water table.

Another object is to provide a system of air conveyors for receiving air from a building and for returning it to the building at a lower temperature, said system including conduits located at a comparatively shallow depth in the earth and means for saturating the earth immediately adjacent thereto and the earth therebeneath extending to the water table, to provide for the transfer of heat from the air and the dissipation thereof in the earth below the water table.

Other objects and advantages will become more fully apparent as reference is had to the 40 accompanying drawings wherein my invention is illustrated, and in which:

Fig. 1 is an elevation of a building and the present underground circulating system, the surrounding earth being illustrated in section,

55 Fig. 2 is a view taken on the line 2—2 of Fig. 1,

Figs. 3 and 4 are sections taken on the lines 3—3 and 4—4, respectively, of Fig. 2 and

Figs. 5 and 6 are sections taken on the lines 5—5 and 6—6, respectively, of Fig. 3.

From a basement wall of the building 1 extends a concrete structure having a portion 2 perpendicular to the wall and lateral extensions 3 and 4, the concrete mix from which the structure is formed being such that the concrete is porous to enable water to readily permeate the 10 same. Within the building 1 is a housing 5 having an air inlet 6 and an air outlet 7 separated by a vertical partition 8. The partition 8 is in line with the end of the portion 2 and two parallel sets of conduits 9 and 10 extend from opposite sides of the partition 8 to a housing 11 located at the juncture of the portion 2 and the lateral extensions 3 and 4. 15

Two parallel sets of conduits 12 and 13 extend through the lateral extension 3 and connect the 20 housing 11 with a hollow housing 14 disposed in the extremity of said extension. A similar pair of conduits 15 and 16 extend through the lateral extension 4 and connect the other side of the housing 11 with a hollow housing 17 located 25 in the extremity of the lateral extension 4.

Within the housing 11 is a vertical cylinder 18 and two partitions 19 and 20 arranged to direct air entering the housing 11 from the conduits 9 into the conduits 12, which convey such air 30 to the housing 14. Within the housing 14 is a cylinder 21 and a partition 22 arranged to direct air from the conduits 12 to the conduits 13, which convey it to the housing 11. A third partition 23 coacts with the cylinder 18 and the partition 19 to direct air from the conduits 13 into the conduits 16, which convey the air to the housing 17. A cylinder 24 and a partition 25 35 in the housing 17 direct the air from the conduits 16 to the conduits 15, which convey the air to the housing 10. The cylinder 18 and the partitions 19 and 23 within the housing 10 direct air from the conduits 15 to the conduits 10 which 40 convey the air to the housing 5 on the outlet side of the partition 8. 45

From the foregoing it becomes apparent that air entering the housing 5 is circulated outwardly through the portion 2, outwardly of the lateral extension 3, inwardly of the extension 3 and outwardly of the extension 4, and then inwardly 50 of the extension 4 and portion 2 to the outlet side of the housing 5. The concrete from which the portion 2 and extensions 3 and 4 is constructed will be at a temperature lower than the normal air temperature, and, therefore, heat 55

will be transferred from the air passing therethrough and dissipated in the surrounding earth.

Extending through the portion 2 and the lateral extensions 3 and 4 are water connected pipes 5 26, and a water control means of the float valve type is diagrammatically illustrated at 27 for maintaining said pipes partially filled with water at all times. The pipes 26 may be of tile capable of discharging water at intervals or throughout 10 their entire length, or they may be perforate tubes as illustrated in Fig. 4.

Water is continuously discharged from the pipes 26 to maintain the concrete from which the portion 2 and extensions 3 and 4 are formed 15 in a saturated condition. The water which permeates the concrete saturates the earth immediately adjacent the sides thereof, and saturates the earth beneath the concrete to the depth of the water table. This saturated earth comprises 20 a much more highly efficient heat conductor than the unsaturated earth and makes possible rapid dissipation of the heat from the air passing through the system.

In the event that moisture contained in the 25 air condenses in the conduits, the same may be removed by any suitable drainage means. For example, in Fig. 3 a water collector 28 adjacent the ends of the tubes 9 has an outlet 29 which is adapted to extend to a point of disposal.

30 What is claimed is:

1. An air cooling system comprising a permeable concrete structure imbedded in and extending a substantial distance beneath the earth surface, a system of conduits in said concrete for 35 receiving air from a building and for returning it thereto, and means for maintaining said con-

crete in a saturated condition throughout substantially the entire length thereof.

2. An air cooling system comprising imperforate conduits for receiving air from a building and for returning the air to the building, a concrete casing incasing said conduits, said conduits and casing being imbedded in and extending a substantial distance beneath the surface of the earth, the concrete of said casing being permeable, and means for saturating said casing. 10

3. An air cooling system comprising imperforate conduits for receiving air from a building and for returning the air to the building, a concrete casing incasing said conduits, said conduits and casing being imbedded in and extending a substantial distance beneath the surface of the earth, the concrete of said casing being permeable, and perforate conduits paralleling the imperforate conduits and adapted to convey water 15 for saturating said casing and the earth there- beneath to the depth of the water table. 20

4. An air cooling system comprising an air inlet and an air outlet, parallel air conduits extending respectively from the inlet and the outlet for a substantial distance beneath the surface of the earth, air conduits extending beneath the surface of the earth a substantial distance laterally from the ends of respective first named conduits, air conduits extending beneath the surface of the earth and connecting the outer ends 25 of said laterally extending conduits, a permeable concrete casing incasing said conduits, and perforate water conveying conduits imbedded in said casing and extending along substantially the entire length of said air conduits. 30
